UNITED STATES PATENT OFFICE.

ROBERT C. LAWHEAD, OF ALLUWE, OKLAHOMA.

GUIDE.

1,143,125.

Specification of Letters Patent. Patented June 15, 1915.

Application filed January 31, 1914. Serial No. 815,747.

To all whom it may concern:

Be it known that I, ROBERT C. LAWHEAD, a citizen of the United States, residing at Alluwe, in the county of Nowata and State of Oklahoma, have invented certain new and useful Improvements in a Guide, of which the following is a specification.

This invention relates to rope winding apparatus and has special reference to that 10 class of apparatus known as "hoists" or apparatus wherein a rope carrying a weight at its free end is wound and unwound upon a suitable drum or windlass provided therefor.

15 The object of the invention is to provide in a rope winding drum, means for automatically guiding the rope during the operation of winding and unwinding, and to so construct and organize the parts of the guide 20 means as a whole, that the preceding coils of rope will be wound upon the drum with the utmost precision and with uniform velocity, and whereby the preceding coils of the rope will also be wound contiguous and 25 in planes parallel with each other.

The invention still further resides in the provision of means of the nature above set forth wherein a shifting and adjusting of the said means may be effected to increase 30 the scope of its usefulness.

The above and additional objects are accomplished by such means as are illustrated in their preferred embodiment in the accompanying drawings, described in the following 35 specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is an elevation illustrating the 45 application of the invention in connection with a hoist or derrick; Fig. 2 is a view illustrating the detail construction of the guide device; Fig. 3 is a detail view of the guide support; Fig. 4 is an enlarged elevation of one of the adjustable bands or collars carried by the support; Fig. 5 is a section on the line 5—5 of Fig. 4; and Fig. 6 is a view illustrating the modified form of guide device.

55 Before proceeding with the description of the drawings, I desire to call particular at-

tention to the fact that while I have evolved my invention with particular reference to its application in connection with a well pulling machine as a guide for the operating rope 60 associated therewith, the same may be readily utilized as a guide means in connection with various types and forms of winding apparatus wherein one or more drums are used.

65 Referring now to the drawings by numerals, it will be seen that the machine consists of an upright or derrick 1 comprising the usual base support 2 and brace beam or beams 3, the latter being disposed in a plane 70 above the usual drum shaft 4 and drums 5 and 6 respectively, mounted thereupon. A substantially U-shaped support member or bracket 7, the extensions of which are screw threaded as at 8 is detachably secured to 75 one of the brace beams or supports 3. The threaded extremities 8 of the extensions of the said bracket pass through openings 9 of the beam 3, nuts 10 being threaded upon the said extensions to retain the said bracket 80 in place. By enlarging the extensions as at 11 and disposing the said enlargement against one face of the said beam as illustrated to advantage in Fig. 3 of the drawings, it is apparent that movement of the 85 support in one direction is limited thereby, the nut 10 serving as a means whereby movement in the opposite direction is prevented.

90 Adjustable collars or bands 11', preferably two in number, are loosely mounted upon the said support 7 and locked in adjusted position thereupon through the medium of set screws or bolts 12 adapted for engagement with the said support. Between the collars 11' and carried by the support 7 is arranged 95 the guide device, designated as an entirety by the numeral 13, employed in connection with the present invention, the said device consisting of a pair of angularly disposed arms 14 arranged substantially V-shaped, 100 said arms converging to a point 15, there continuing as one as indicated at 16 until finally terminating in a coiled or helical extension 17, the latter providing a loop 105 through which either of the ropes 18 or 19 of the hoisting apparatus are adapted to pass. The diverging extremities of the arms 14 each terminate in an eye 20 arranged to embrace the said support 7 to effect a loose connection for the said guide.

110 Referring now to the modified form of guide device illustrated in Fig. 6, the nu-

meral 21 designates the said guide as an entirety, at one end of which an eye 22 is formed and at the opposite end a coiled or helical extension 23 is formed, the latter serving the same purpose as the extension 17 of the converged guide means, and the former the same purpose as the eye 20 aforesaid. The said guide member being loosely mounted upon the support 7, and arranged to loosely embrace the rope or cable acted upon, it is apparent that the latter during a winding or unwinding operation will be guided back and forth to wind upon the drum with the utmost precision, the said 15 rope or cable. By adjusting the collars or bands 11' it is apparent that the path of movement of the guide device 13 may be limited to suit the demand made thereupon, or to correspond with the size of the drum 20 over which the cable or rope acted upon is arranged.

From the above, taken in connection with the accompanying drawings it is apparent that by providing a support 7 of a size to 25 extend beyond the extremities of the respective drums, that the said guide device may be removed from engagement with the cable of one drum and quickly shifted to the cable of the adjacent drum by simply adjusting 30 the collars or bands 11 longitudinally of the support or bracket from which the guide device is hung to depend.

To fit the cable within the loop formed by the coiled extension 17 of the guide means, 35 all that is necessary is to first pass the said rope in the space indicated *a*, then over and into the space indicated *b*, and finally into the space indicated *c*, in which event the rope is entirely surrounded or embraced in such 40 a way as to be subsequently guided back and forth from one to the other end of the drum in the desired manner.

It will be understood that the above description and accompanying drawings comprehend only the general and preferred embodiment of my invention and that various 45

minor changes in details of construction, proportion and arrangement of parts may be made within the scope of the appended claims and without sacrificing any of the 50 advantages of my invention.

Having thus fully described my invention, what I claim as new and desire to secure by Letters Patent, is:—

1. In combination, axially alined drums, 55 each drum having a flexible element wound thereon, supporting means for the drums, a bracket mounted on said supporting means, the bracket extending parallel with the axes of the drums, a pair of relatively adjustable 60 stop devices mounted on said bracket, and a single guide device hung to depend from the bracket and to removably engage one or the other of said flexible elements, said guide device being limited in its movement by the 65 stop means aforesaid, as and for the purpose set forth.

2. In combination with a plurality of drums arranged in axial alinement, each drum having a flexible element wound thereupon, a bracket, substantially U-shaped, of a length sufficient to extend beyond the remote terminals of the alined drum, a guide device hung to loosely depend from the said bracket, 70 said device being movable longitudinally 75 thereof, collars adjustable upon the bracket to restrict longitudinal movement of said guide device to the length of any one of said drums, and a double coil forming a part of the said guide device, said coil being directly 80 engageable with the element acted upon, said coiled portion of the guide being movable vertically and longitudinally relatively 85 to the drum during a winding and unwinding operation, as and for the purpose set forth.

In testimony whereof I affix my signature in presence of two witnesses.

ROBERT C. LAWHEAD.
